UNITED STATES PATENT OFFICE.

GUSTAV TRESENREUTER, OF BERLIN, GERMANY.

REVOLVER.

SPECIFICATION forming part of Letters Patent No. 710,821, dated October 7, 1902.

Application filed January 23, 1902. Serial No. 81,778. (No model.)

To all whom it may concern:

Be it known that I, GUSTAV TRESENREUTER, engineer, a subject of the Emperor of Germany, and a resident of Plan Ufer 60, Berlin, 5 Germany, have invented new and useful Improvements in or Relating to Revolvers; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 This present invention relates to a revolver arranged in the handle of a walking-stick, umbrella, or the like. The construction of the revolver is particularly distinguished by all its constitutive parts being arranged in a 20 comparatively limited space.

In the drawings, Figure 1 is a top plan view of the handle of a walking-stick containing the revolver. Fig. 2 is an elevation of the latter with the side removed. Fig. 3 is a sectional elevation with the opposite side wall removed. Fig. 4 shows the revolver ready for firing, the parts being partly in section. Fig. 5 shows the same position of the firing parts from the opposite side. Fig. 6 is the revolver 25 after firing with the trigger still under the influence of the finger. Fig. 7 is a front elevation of the empty revolver-cylinder. Fig. 8 shows the revolver-cylinder charged with a cartridge and under the influence of the feeding lever or pawl. Fig. 9 is a vertical section on the line A B of Fig. 3, and Figs. 10 and 11 are details of the mechanism.

The revolver consists of two parts 1 and 2 of a metal frame that form the cane-handle 40 disposed at right angles to the stick portion of the cane, the part 2 being in rigid connection with the support or stick-socket 3, while the part 1 can be turned upward about a hinge 4. Between the parts 1 and 2 is rotatably arranged a cartridge-cylinder 5, provided on its rear side with teeth or notches 6. A horizontal bolt 8, screwed into the vertical cross-wall 7, serves as a support for the cylinder, and a flat spring 47 is preferably arranged above the latter with the object of preventing it from having too much free play and to act as a brake upon it. The rear por-

tion contains the charging, adjusting, and firing devices, as well as the locking device for securing the trigger, while the front portion 55 2 contains the barrel 9.

In the lower part of the rear portion 1 is a slot or recess 10, which normally receives the trigger 11 when the revolver is not in use. The trigger 11 is connected by a hinge 12 60 with a pivoted flat plate 14, having its fulcrum at 13 and acting in the manner of a bolt, while its downward motion is limited by an abutment 15.

The flat plate 14 is under the influence of a 65 strong flat spring 16 and is provided with a vertical slot 17, in which is guided the pin 18 of a pivotally-mounted plate 20, fulcrumed at 19. Moreover, the flat plate 14 carries on its end adjacent to the cylinder the feeding-pawl 22, mounted upon a small stud 21 and extending through a slot 23, Fig. 10, in the wall 24 and engaging with the teeth 6 on the cylinder 5 and being constantly pressed forward by a small spring 25.

The upper part of the flat plate 14 has an 75 offset 26, which is on a level with the lower end of a small spring-controlled bell-crank lever 27. This lever is mounted on a flat plate 28, the forward end of which is shaped 80 to form the percussion-bolt 29, while its rear end serves as an abutment 46 for the plate 20. This plate 28 is guided horizontally by means of a pin 30, working in a slot 32 in the wall 31, Fig. 3. A rod 34 with a strong spiral 85 spring 33 and capable of extending through an opening 34 into the metal frame 1 forms the extension of the plate 28.

For feeding and locking the cylinder with its cartridges 36 a bell-crank lever 38, fulcrumed at 37, is arranged on the narrow portion of the wall 24. This lever is operated by the pin 30, extending through the slot 32, Fig. 3, said pin pressing the rear end of the bell-crank lever 38 after overcoming the tension of the spring 39 in an upward direction, whereby the other end engages with the projection 40 in one of the series of recesses 41 around the cylinder 5, thereby locking the latter. This arrangement prevents the cylinder 95 from further rotation to the right, while its rotation in the other direction is prevented by the continuous engagement of the pawl 22 100 with the teeth of the cylinder.

operation of the revolver is as follows: detaching the parts 1, 2, and 3 of the g by depressing the button 44, Fig. 3, a catch-hook 43 42 the part 1 is turned its hinge 4 in the upward direction, enabling the operator to charge the re. After resetting the casing the trigger brought into position. (Shown in Figs.

3.) Now on embracing the neck por. of the stick with the hand the trigger 11, her with the flat plate 14, is brought by s of the thumb into the position ready ing, and the bolt 28 is brought into a like on on overcoming the springs 16 and 33 e offset 26 and the bell-crank lever 27. e same time the plate 20, arranged be the flat plate 14, is carried along in the 7, and its upper part is thus displaced right or forwardly. In the same way awl 22 is raised on account of the rota of the flat plate 14 about its pivot and gaging with the teeth of the cylinder the latter to the extent of one cartridge in the direction of the arrow Fig. 8. e same time the cylinder is released the locking-lever 38, as the tension of spring 39 is no longer opposed, Figs. 4. The firing is effected as soon as the 26 has passed the lever-arm 27. The spring 33 is thus released, and the percus-bolt 29 is driven through the opening to the cartridge, which, however, is only ole when the plate 20 is turned forward the flat plate 14, and consequently the ent 46 of the percussion-bolt finds its clear on its return after firing the car. Fig. 6. At the same moment the cyl is locked again and only after comy releasing the trigger 11 does the mech- in connection with the latter return the influence of the flat spring 16 to tial position. The plate 20 takes again rtical position and presses the percus-bolt carrier 28 slightly to the left and the percussion-bolt into the opening

45 and out of the path of the cartridge-head. Finally, it may be remarked that all con-structive details of the revolver are covered up by protecting-plates 48, which by means of screws 49, Fig. 4, or the like are connected 50 together.

Having thus described my invention, I claim as new and desire to secure by Letters Patent—

1. In a revolver for a cane, the combina- 55 tion, of a cane-handle frame comprising two parts hinged together and having a central socket portion forming the handle of the re- volver, means for locking said parts in closed position, a barrel formed in one of said parts, 60 a cylinder, firing mechanism arranged in the other of said parts, and a trigger operated in forward direction to actuate the firing mech- anism, substantially as set forth.

2. In a revolver mechanism for a cane, the 65 combination, with a handle, of a rotatable cylinder having circumferential notches, a pivotally-mounted spring-actuated flat plate, an adjustable trigger attached thereto, said flat plate being slotted, a plate pivotally 70 mounted and having a pin guided in the slot of said flat plate, means connected with said flat plate for rotating said cylinder, a spring- actuated longitudinally-movable percus- 75 sion-bolt, an abutment on said percus-sion-bolt adapted to coöperate with said plate, a spring- controlled lever adapted to engage with the notches of said cylinder, means on said percus-sion-bolt for actuating said lever, and means on said flat plate for actuating said 80 percus-sion-bolt, substantially as set forth.

In testimony that I claim the foregoing as my invention I have signed my name in presence of subscribing witnesses.

GUSTAV TRESENREUTER.
